(57) **CLAIM**

The ornamental design for a display screen with graphical user interface, as shown and described.

DESCRIPTION

FIG. 1 is a front view of a display screen with a first variant of a graphical user interface according to our new design.

FIG. 2 is a second embodiment thereof.

FIG. 3 is a third embodiment thereof.

FIG. 4 is a fourth embodiment thereof.

FIG. 5 is a fifth embodiment thereof; and,

FIG. 6 is a sixth embodiment thereof.

The outermost broken lines in all figures illustrate the display screen. The remaining broken lines in FIGS. 1 and 4 illustrate portions of the graphical user interface. None of the broken lines form part of the claimed design.
